FIG. 2

FIG. 1 is a perspective view showing the front and one side of the hamper embodying my new design;

FIG. 2 is a top plan view thereof.

The opposite side and the back of the hamper shown in FIG. 1 is the same as the front and side shown.

The part within the openings in the outer housing, indicated as fabric, represents a removable bag.

I claim:

The ornamental design for a hamper, as shown and described.
